UNITED STATES PATENT OFFICE.

CASSIUS M. GAY, OF ALLEGHENY, PENNSYLVANIA.

GAS-EXPLOSIVE DEVICE AND COMPRESSOR FOR REVERSIBLE ENGINES.

No. 841,859.

Specification of Letters Patent.

Patented Jan. 22, 1907.

Application filed February 6, 1904. Serial No. 192,305.

To all whom it may concern:

Be it known that I, CASSIUS M. GAY, a resident of Allegheny, in the county of Allegheny and State of Pennsylvania, have invented a new and useful Improvement in a Gas-Explosive Device and Compressor for Reversible Engines; and I do hereby declare the following to be a full, clear, and exact description thereof.

My invention relates to gas, gasolene, oil, or similar engines; and its object is to utilize the pressure generated by firing explosive gases or mixtures thereof for the operation of engines or motors, and especially reversing engines, thereby to reduce the weight and increase the efficiency, reliability, and ease of control of reversing engines of all kinds, and especially for use on self-propelled vehicles, automobiles, pleasure-boats, and the like.

In an application filed December 28, 1903, Serial No. 186,903, I described and claimed an arrangement of apparatus for operating reversing and similar engines by means of pressure generated by firing explosive gases or mixtures thereof and storing the same in a pressure-tank, the particular arrangement of the apparatus shown and claimed in said application being such as to utilize the energy of the several explosions to compress previously-exploded charges and force the same into a pressure-tank, from which said gases were to be taken to an ordinary reversing engine, the latter thus operating in the same manner as an ordinary reversing steam-engine. By this means I overcame the severe vibrations caused by explosive-engines, did away with the complicated and heavy speed-reducing and reversing gearing, and obtained all the efficiency of control of an ordinary steam-engine, but did away with the liability of freezing and the heavy boilers, burners, and water-tank necessary for steam-engines.

The present invention relates to the same subject-matter as my application above described and has the same general objects in view. The apparatus shown in my prior application delivers the exploded gas of one explosion into the pressure-tank at the terminal pressure of the succeeding explosion. The present invention is an apparatus which will deliver the exploded gas to the pressure-tank or engine at the initial pressure of each explosion, whereby a higher degree of pressure may be secured and greater efficiency and economy attained.

In the accompanying drawings, Figure 1

is a sectional diagram illustrating my invention, and Fig. 2 is a similar diagram illustrating the use of two explosion-cylinders.

In carrying out my invention I make use of a reversing engine 1, which may be of any well-known type at present used for automobiles and similar purposes and designed to use steam. Instead of connecting this engine to a boiler I connect it to a pressure-tank or accumulator 2, which in its general functions may be said to take the place of the steam-drum of a boiler when the engine is operated by steam. With my invention, however, this tank serves to store exploded gases under pressure.

The gases to be used may be of any form at present used in explosive-engines, being either specially-produced gases or resulting from the evaporation of gasolene or other oils, these gases being used either alone or mixed with air, as is the usual custom. The gas or mixture of gas and air is supplied by the pipe 4 and is forced, by means of a pump 5, having a suction-valve 6 and discharge-valve 7, into an explosion-chamber 8. The pump 5 may be driven by any suitable motor, such as the small gasolene-motor 9 or any other suitable motor driven from an independent source of power.

The pump is connected to one end of the explosion-cylinder by means of a pipe 10, leading through the head 11 of said cylinder, by means of a port which is controlled by an automatically-operating valve 12, the latter opening inwardly with reference to the cylinder-chamber and being normally held on its seat by a spring 13. This head of the cylinder is also provided with a discharge-port 14, which is connected, by means of a pipe 15, with the pressure-tank 2. In the cylinder is a piston 16, which is normally held against the head 11 by means of a spring 17 or equivalent arrangement.

The pipes connected with the inlet and outlet ports are provided with positively-actuated valves 18 and 19, respectively. These may be of various forms, being shown as ordinary two-way cocks. These valves may be operated in any suitable way, but preferably from the piston 16. This may be accomplished by providing said piston with guide-rods extending in one or both directions through stuffing-boxes in the heads of the cylinder. Preferably, however, the piston 16 will be entirely inclosed and not provided with even a guide-rod. Projecting

- through the heads of the cylinders are a pair of plungers 21 and 22, which lie in the path of movement of the piston and will be actuated thereby. The rod 21 is connected to a pair of levers 23 and 24, the former being connected by a link 25 to an arm 26 on the inlet-valve 18, while the latter is connected by a similar link 25 to an arm 27 on the outlet-valve 19. The rod 22 contacts with one arm of a bell-crank lever 29, the opposite arm of which is connected to a reciprocating member 30, which at its outer end is provided with a hook 31 for engaging a projection on the end of the link 25 when the latter descends, said reciprocating member 30 being held under tension of a spring 32, so that it will serve as a lock for holding the link 25 in its depressed position. A spiral spring 33 bears against the lever 24 and tends to restore the valves to their normal position when the lock is released, as it will be when the piston 16 actuates the rod 22. By means of the levers 23 and 24 the valves 18 and 19 are connected together, so that they will operate in unison and will be moved in one direction when the piston 16 contacts with the rod 21 and in the opposite direction when the piston contacts with the rod 22, thus disengaging the lock 31 from the link 25 and permitting the spring 33 to move the valves. These two valves are oppositely arranged, so that when the inlet-valve 18 is open the outlet-valve 19 will be closed, and vice versa.
- 35 The upper end of the cylinder 8 is connected to the pressure-tank 2 by means of a pipe 36, having therein a check-valve 37 so arranged as to permit the pressure to pass from the tank to the cylinder, but not in the opposite direction. A pipe 38 also connects the pressure-tank with the cylinder and enters the latter at a point just above the piston 16 when the latter is in its normal or depressed position.
- 45 The explosions in the cylinder 8 may be produced by any suitable igniting device, and I have shown diagrammatically a spark-plug 39, projecting through the head 11 of the cylinder and connected in circuit with a suitable source of electrical energy, such as the battery 40, and adapted to be energized by any suitable means, such as the rotating circuit-closing device 41, actuated, preferably, by the motor 9, the arrangement being such as to secure, if necessary, one explosion for each stroke of the pump, but preferably only once for every several strokes of the charging-pump, as may be found necessary or desirable.
- 55 In order to prevent the overcharging of the pressure-tank 2 and also prevent waste of the explosive mixture or gas, means is provided for stopping the flow of explosive mixture to the explosion-cylinder when the pressure in the tank 2 has reached the desired de-
- gree. The means for this purpose comprises a by-pass pipe 45, leading from the discharge side 7 of the pump back to the suction side 6 thereof. In this by-pass I place a controlling-valve, that shown being an ordinary three-way cock 46, which controls both the by-pass pipe 45 and the pipe 10, leading to the explosion-cylinder, the cock being so arranged that in one position it will open the pipe to the cylinder and close the by-pass and in the other position will open the by-pass and close the passage to the explosion-cylinder. This valve will be controlled by any suitable intermediate mechanism from the pressure-tank 2, such as connecting to 70 said tank a fitting having therein a piston 47, which is held inwardly by a strong spring 48 or counterweight and is acted upon by the pressure medium in the tank 2. This piston will be connected by any mechanical means to the controlling-cock 46, and in the drawings I have shown a bell-crank lever 49 connected to the piston and connected, by means of the links 50 and 51 and intermediate bell-crank-lever 52, to an arm 53 on the 75 cock 46. In actual practice the controlling-valve 46 will be placed in close proximity to the tank 2, so that the long links 50 and 51 and other connecting means can be dispensed with. The diagram shown in the drawings 80 merely represents the essential elements of the invention and is not intended to illustrate the exact location of the several parts, the parts having been placed in the position shown in the diagram for the sake of clearness and to prevent confusion as to the relations and functions thereof.
- 85 The operation of the apparatus described is as follows: The gas or other explosive mixture will be forced by the pump 5 into the explosion-cylinder 8 between the head 11 and piston 16, the inlet-valve 18 being open and the outlet-valve 19 being closed, the pump giving sufficient pressure to unseat the check-valve 12 and probably to 90 slightly move the piston 16. As soon as a sufficient charge has been forced into the cylinder it will be exploded, and the back pressure caused thereby will seat the valve 12 and prevent the expansive force of the exploded gas from escaping back into the pump. The discharge-valve 19 will be closed at the time of the explosion, and the expansive force of the explosion will move the piston 16 toward the opposite end of the cylinder. As soon, however, as the piston is moved a distance equal to its thickness it will uncover the port connected by the pipe 38 to the pressure-tank, and as a consequence the pressure of the explosion at substantially 95 the initial pressure of the explosion will escape directly into the tank and from there will pass the check-valve 37 and into the upper end of the cylinder behind the piston 16. As a consequence the gas-pressure on both 100
- 105
- 110
- 115
- 120
- 125
- 130

sides of the piston will be balanced, and the spring 17 will be able to force the piston 16 to its normal position. The force of the explosion, however, will have driven the piston 16 to such a distance as to strike the plunger 21, thus forcing the latter outwardly and through the connecting-levers 23 and 24 moving the valves 18 and 19 to the reverse position—that is, closing the inlet-valve and opening the outlet-valve. The piston 16 will be cushioned at the limit of its movement both by the spring 17 and by the pressure of the gas behind the same; the latter being prevented from again escaping to the tank 2 by reason of the check-valve 37. In the movement of the valves to their reverse positions the projection on the lower end of the link 25 will be caught by the hook 31 of the member 30, thus locking the valves in this position—that is, with the outlet-valve open and the inlet-valve closed. When the spring 17 returns the piston 16 to its normal position, the latter will force all of the exploded gas in the lower end of the cylinder 25 out through the port 14, outlet-valve 19, and pipe 15 to the tank 2, so that practically no exploded gas will be between the piston and the head 11 of the cylinder. At the limit of the movement of the piston 16 it will contact with the rod 22, and the latter through the bell-crank lever 29 will actuate the member 30 so as to release the link 25, thus permitting the spring 33 to return the valves to their initial position, so that the pump will again force a charge under the piston 16, which charge will at the proper time be again exploded and the foregoing operation repeated.

It will be seen that at all times there will be above the piston 16 a pressure equal to that in the tank 2; but the force of the explosion will be sufficient to drive the piston 16 against this pressure, as well as against the spring 17, and said spring and the gas confined between the piston and the upper head of the cylinder will act as a cushion for the piston. As soon as the piston has moved only a short distance the explosive mixture will escape directly into the cylinder and will then equalize itself above and below the piston. In this way the pressure-gases are delivered to the tank 2 at the initial pressure of the explosions, and the spring 17 will merely have to move the piston 16 back to its initial position. The automatically-closed valve 12 prevents the pressure of an explosion from backing into the pump, while the positively-actuated valve 18 prevents the pump from forcing a fresh supply of gas into the cylinder before the piston 16 has been entirely returned to its normal position. The positively-actuated valve 19 prevents the force of the explosion from passing directly to the tank 2 at the moment of explosion, thus causing it to expend itself in starting the move-

ment of the piston 16 toward the opposite end of the cylinder; but said valve permits all the exploded gas to be driven from between the piston and the head 11 of the cylinder.

As soon as the pressure in the tank 2 has reached the desired tension the piston 47 will be moved against its controlling spring or weight and through the links and bell-crank levers shown the three-way cock 46 will be turned to close the passage to the explosion-chamber 8 and open the by-pass 45, thus permitting the pump to run idly, the explosive mixture being merely circulated from the discharge side of the pump to the suction side thereof. This prevents the accumulation of dangerous pressures in the tank 2 and also prevents the waste of the explosive mixture. As soon as the pressure in the tank 2 falls materially the piston 47 will be moved inwardly by its balancing spring or weight, thus moving the three-way cock 46 to its original position and permitting the explosive mixture to be again fed to the explosion-chamber.

The pressure generated by the explosion of the gases is therefore compressed and stored in the tank 2. From here it will be taken directly to the engine 1 in the same manner that steam is taken from the steam-space of a boiler to the engine, and said engine will be driven and operated in exactly the same manner as though steam were used, thus securing the ease of control of a steam-engine and at the same time entirely dispensing with the boiler, heater, and connections and also eliminating the danger of freezing. The engine is therefore practically a gas-driven engine; but as it is of the reversing type it can be run at any desired speed and can be readily reversed, thus dispensing with the usual speed-reducing, reversing, and friction gearing and inclosing casing employed with explosive-engines.

The size of the pressure-tank is not material. In fact, it may be reduced so that it is nothing more than a pipe serving to connect the pipes 15, 36, and 38, coming from the explosion-cylinder.

It is obvious that many modifications in the details of my invention may be made without departing from the spirit thereof, most of the mechanical features shown being capable of being displaced by other means for producing the same result, such as employing an air-cushion in lieu of the spring for returning the piston.

If desired, a series of explosion-cylinders 8 may be employed in connection with a single pressure-tank 2. In Fig. 2 such an arrangement is shown, the tank 2 having connected thereto a pair of explosion-cylinders 8 and 8^a. The details of pipe-and-valve arrangements for each of these cylinders are identical with the cylinder shown in Fig. 1. The igniting devices 39^a 39^b of the two cylinders are

connected to a rotary circuit-maker 41^a, which is so arranged as to close the circuit to these igniting devices in succession, so that the explosions in the two cylinders will take place alternately. Many of the details have 5 been omitted in this view to prevent confusion; but the principle thereof can be extended so that any number of compression-cylinders may be used with a single pressure-tank, the only essential being that the igniting devices shall be so arranged as to cause 10 explosions in the several cylinders in regular succession.

A single pump may be used for supplying 15 all of the explosion-cylinders or a separate pump may be used for each of the cylinders.

What I claim as my invention, and desire 20 to secure by Letters Patent, is—

1. In apparatus of the character specified, 25 the combination of an explosion-cylinder, an imperforate piston therein, inlet and outlet ports into said cylinder, valves in said ports operated from said piston, igniting means in said cylinder, means for delivering the exploded gases from said cylinder at substantially the initial pressure of each explosion, and an equalizing-passage between the two ends of the cylinder.

2. In apparatus of the character described, 30 the combination of an explosion-cylinder, an imperforate piston therein, an equalizing-passage between the two ends of said cylinder whereby a previously-exploded charge holds said piston normally at one end of said cylinder, means for forcing gas into the cylinder between the piston in its normal position and the adjacent head of the cylinder, igniting means in said cylinder, and means for delivering the exploded gases from said 35 cylinder at substantially the initial pressure of each explosion.

3. In apparatus of the character described, 40 the combination of an explosion-cylinder having no communication to the atmosphere, a piston therein, means for normally holding said piston against one head of said cylinder, an inlet-port arranged to deliver gas between said head and piston when in its normal position, igniting means adjacent to 45 said head arranged to explode the charge of gas when said piston is in its normal position, an outlet from the cylinder adjacent to said head, whereby exploded gas is delivered from the cylinder at substantially the initial pressure of each explosion, and connections arranged to equalize the pressure on opposite 50 sides of said piston.

4. In apparatus of the character described, 55 the combination of an explosion-cylinder having no communication to the atmosphere, a piston therein, means for normally holding said piston against one head of said cylinder, an inlet-port arranged to deliver gases between said head and piston when the latter is in its normal position, means ar-

ranged to ignite the charge of gas with the piston in its normal position, an outlet from the cylinder adjacent to said head, and a pipe and valve arranged to admit the pressure of prior explosions into the cylinder on the opposite side of the piston. 70

5. In apparatus of the character described, 75 the combination of an explosion-cylinder having no communication to the atmosphere, a piston therein, means for normally holding said piston at one end of said cylinder, means for exploding successive charges of gases between said piston and the head of the cylinder with which it is normally in contact, and a pipe arranged to admit the pressure of prior explosions into the cylinder on the opposite side of said piston. 80

6. In apparatus of the character described, 85 the combination of an explosion-cylinder, a piston therein, means for normally holding said piston at one end of said cylinder, valve-controlled inlet and outlet ports to the same end of said cylinder, igniting means in said cylinder, and a pipe and valve arranged to admit the pressure of prior explosions into the 90 cylinder on the opposite side of the piston.

7. In apparatus of the character described, 95 the combination of a single explosion-cylinder having no communication to the atmosphere, a piston contained within said cylinder, valve-controlled inlet and outlet ports to said cylinder, said valves being so arranged that when one is open the other is closed, means controlled from said piston for operating said valves, means for normally holding said piston against one head of said cylinder, means for exploding a charge of gas between said head and said piston, and means for delivering the exploded gases from said cylinder at substantially the initial pressure of 100 each explosion. 100

8. In apparatus of the character described, 105 the combination of a single explosion-cylinder, having no communication to the atmosphere, an imperforated piston therein, igniting means in said cylinder, inlet and discharge valves for said cylinder so arranged that when one is open the other is closed, means controlled by the piston when moving in both directions for shifting said valves, 110 means for moving the piston against the force of an explosion, a pressure-tank, and pipe connections between the same and cylinder so arranged that the exploded gases are delivered to the pressure-tank at substantially 115 the initial pressure of each explosion. 120

9. In apparatus of the character described, 125 the combination of a single explosion-cylinder having one communication to the atmosphere, an imperforate piston therein, an igniter in said cylinder, inlet and discharge valves for said cylinder, said valves being so arranged that when one is open the other is closed, means projecting into the cylinder into the path of the piston and arranged to 130

operate said valves, means for moving the piston against the force of an explosion, a pressure-tank, and pipe connections between the same and cylinder so arranged that the 5 exploded gases are delivered to the pressure-tank at substantially the initial pressure of each explosion.

10. In a device of the character described, the combination with an explosion-cylinder, a piston therein, igniting means in said cylinder, inlet and discharge valves for the cylinder so arranged that when one is open the other is closed, a rod projecting into the cylinder into the path of the piston and 15 connected directly to the valves and arranged to shift them in one direction, a spring for returning the valves to their normal position, a lock for restraining said spring against action, and releasing means for said lock arranged to be actuated from the piston in the cylinder.

11. In apparatus of the character described, the combination with a single explosion-cylinder, an imperforate piston therein, means for normally holding said piston at one end of the cylinder, means for forcing an explosion charge between said cylinder end and the piston, means for igniting the gas in the cylinder, between said cylinder end and piston, inlet and discharge valves for said cylinder so arranged that when one is open the other is closed, means operated by the piston when moving in both directions to shift said valves, a pressure-tank, and pipe connections 35 between the same and the cylinder so arranged that the exploded gases are delivered to the pressure-tank at substantially the initial pressure of each explosion.

12. In apparatus of the character described, the combination of an explosion-cylinder, an imperforate piston therein, means for normally holding said piston against one head of the cylinder, means for forcing an explosive charge between said piston and said 45 cylinder-head, igniting means, and a normally open outlet from the cylinder on the opposite side of the piston when in its normal position.

13. In apparatus of the character described, the combination of an explosion-cylinder, a piston therein, means for normally holding said piston at one end of the cylinder, a valve-controlled inlet-port to the cylinder, means for igniting the gas in said cylinder on 55 one side of the piston, a pressure-tank, and a normally open passage from the tank to the cylinder on the opposite side of the piston when in its normal position.

14. In apparatus of the character described, the combination of an explosion-cyl-

inder, a piston therein, means for normally holding said piston at one end of the cylinder, a valve-controlled inlet-port into the same end of said cylinder, means for igniting the gas in said cylinder on one side of the piston, 65 a pressure-tank, and a normally open passage from the tank to the cylinder on the opposite side of the piston when in its normal position.

15. In apparatus of the character described, the combination of an explosion-cylinder, a piston therein, means for normally holding the same at one end of the cylinder, a valve-controlled inlet-port in the same end of said cylinder, means for exploding gases in said cylinder, a pressure-tank, a pipe connecting the same with the end of the cylinder opposite that at which the piston normally rests, a check-valve in said pipe arranged to prevent gases from passing from the cylinder to the tank, and a pipe connecting the inlet 70 end of the cylinder with said tank.

16. In apparatus of the character described, the combination of an explosion-cylinder, a piston therein, means for normally holding the piston at one end of the cylinder, 85 a valve-controlled inlet-port in the same end of the cylinder, means for exploding the gas in said cylinder, a pressure-tank, a normally open pipe connecting said tank with said cylinder and entering the latter in close proximity to the piston when in its normal position a pipe connecting the opposite end of the cylinder with the pressure-tank, and a check-valve in said last-named pipe arranged to prevent the gas from passing from the cylinder to the tank. 90

17. In apparatus of the character described, the combination of an explosion-cylinder, a piston therein, means for normally holding said piston at one end of said cylinder, valve-controlled inlet and outlet ports entering the cylinder at the same end, means for igniting gases in said cylinder, a pressure-tank, a pipe connecting the same to the outlet-port of the cylinder, a pipe connecting 100 the tank with the opposite end of the cylinder, a check-valve in said last-named pipe arranged to prevent gas from passing from the cylinder to said tank, and a normally open pipe connecting the tank with the cylinder 105 and opening into the latter in close proximity to the piston when in its normal position. 110

In testimony whereof I, the said CASSIUS M. GAY, have hereunto set my hand.

CASSIUS M. GAY.
